(57) **CLAIM**

The ornamental design for a paint brush with integrated hanger, as shown and described.

DESCRIPTION

FIG. 1 is a top, front, left perspective view of a paint brush with integrated hanger showing our new design;

FIG. 2 is an enlarged front elevation view thereof taken from section 2 in FIG. 1;

FIG. 3 is a rear elevation view thereof;

FIG. 4 is a front elevation view thereof;

FIG. 5 is an enlarged front elevation view thereof taken from section 5 in FIG. 4;

FIG. 6 is left side elevation view thereof;

FIG. 7 is a right side elevation view thereof;

FIG. 8 is a top plan view thereof; and,

FIG. 9 is a bottom plan view thereof.

The uniform broken line showing in FIGS. 1-8 is for the purpose of illustrating portions of the paint brush with integrated hanger assembly and forms no part of the claimed design.

The dot-dash broken line showing in FIGS. 1, 3 and 4 depicts a boundary line, and forms no part of the claimed design.

The dot-dot-dash broken lines shown in FIGS. 3 and 4 depict enlarged view indicators and form no part of the claimed design.
